STOP MECHANISM FOR STEP-BY-STEP PLUNGERS

Filed May 10, 1949

UNITED STATES PATENT OFFICE

2,627,757

STOP MECHANISM FOR STEP-BY-STEP
PLUNGERS

Harold S. Austin, Dallas, Tex.

Application May 10, 1949, Serial No. 92,484

10 Claims. (Cl. 74—565)

1

The present invention relates to stop mechanisms for step-by-step plungers and, more particularly, to such structure of hypodermic syringes, and constitutes an improvement over such structure as shown in my U. S. Letters Patent No. 2,457,859 issued January 4, 1949.

A general object of the present invention is to provide in such a hypodermic syringe unique stop mechanism for the step-by-step plunger which is of simple construction, readily and economically manufactured, the parts being easily assembled and then positive in operation efficiently to assure delivery of successive dosages of predetermined amounts; the mechanism being simpler and possibly of a more desirable character than that disclosed in my above identified patent.

A more specific object of the present invention is to provide such stop mechanism in the form of cam operated parts so constructed and arranged as to assure compactness and to permit use of circular housing structure requiring a minimum of machining and well adapted to economical mass production.

A further object of the present invention is the provision of structural embodiments of such stop mechanism which are readily constructed and allow efficient use and operation thereof.

Other objects of the invention will in part be obvious and will in part appear hereinafter.

The invention accordingly comprises the features of construction, combination of elements and arrangement of parts, which will be exemplified in the construction hereinafter set forth, and the scope of the invention will be indicated in the claims.

For a fuller understanding of the nature and objects of the invention, reference should be had to the following detailed description taken in connection with the accompanying drawing, in which:

Fig. 1 is an exploded perspective, with parts broken away, of a hypodermic syringe embodiment of the present invention, showing the parts of the stop mechanism as viewed from above;

Fig. 2 is a top plan view of certain parts of the hub assembly of the structure shown in Fig. 1, with the plunger shaft shown in section and the control lever or manual button swung to the left to permit the stop on the left side to be biased toward stop-engaging position of that shaft;

Fig. 3 is a view similar to Fig. 2, with parts broken away, showing the stop on the left side snapped into engaging position with respect to the shaft as the latter is pushed inward or downward to discharge a dosage of predetermined amount;

Fig. 4 is a view similar to Fig. 3, showing the control lever moved to a central neutral position during its swing over to the right side;

Fig. 5 is a view similar to Figs. 3 and 4 showing

2

the control lever swung to the right side to permit the right hand stop to assume a position similar to the position of the left hand stop, as shown in Fig. 2;

5 Fig. 6 is a view similar to Fig. 4 of a modified form of the structure shown therein, simplified for commercial production; and

Fig. 7 is a top plan view similar to Figs. 2 to 5 inclusive of another embodiment of the present invention more nearly similar to the structure shown in Fig. 7 of my above identified patent with respect to the housing construction.

Referring to the drawing, like numerals identify similar parts throughout. As will be seen from Figs. 1 to 5 inclusive, a preferred embodiment of the present invention comprises a hub assembly 10 adapted to be mounted on the top end of a casing barrel structure (not shown) which may be similar to that described in my above identified patent. The hub assembly 10 preferably includes a cylindrical base member 11, to the bottom end of which is preferably secured a pair of diametrically-opposed, laterally extending wings 12, 12 to serve as finger grips. 15 The top end of the cylindrical member 11 is preferably counterbored to provide a socket 13 therein having a flat bottom 14 and a circular side wall 15, with the latter notched at 16 to provide for projection therefrom of the control lever or thumb button. Concentrically of the socket 13, the cylindrical base member 11 is provided with a circular hole 17 reciprocatively to receive therethrough a circular plunger shaft 18.

20 The plunger shaft 18 has a plurality of longitudinally-extending series of abutment means to cooperate with stop means housed in the socket 13 of the hub base member 11, and for this purpose preferably is provided with a plurality of pairs of such series of such abutment means, 25 preferably in the form of notches. A cooperative pair thereof preferably is arranged along the shaft 18 on diametrically opposite sides as indicated respectively at 19 and 20, with those in one series staggered with respect to those in the other series. Each of the notches 19—19 and 30 20—20 has an upwardly and inwardly sloping face 21 on the bottom side thereof to permit stop means readily to slide thereinto, and a substantially flat, transversely-extending top face 22 to 35 provide the stop abutment engageable against the stop means when snapped into any one of those notches, so as to limit and stop movement of the plunger shaft. Thus, the distance longitudinally of the shaft 18 between abutment face 22 of one notch 19 and abutment face 22 of the 40 next succeeding diametrically-located notch 20 predetermines the length of longitudinal shaft movement during one step of motion thereof. The length of the next step of motion of the 45 plunger shaft, of course, is predetermined by the 50 55 60

longitudinal distance along the shaft 18 between abutment face 22 of that latter notch 26 and the abutment face 22 of the next succeeding notch 19. As previously made clear in this art, more particularly by reference to my above identified patent, such plunger shaft means preferably is also provided with two other opposed series of notches spaced different distances apart along the plunger shaft 18 so as to permit delivery from the hypodermic syringe of dosages of different predetermined amounts. There is shown at 23 a notch of one of those latter series of abutment means.

The plunger shaft mechanism which is housed in the socket 13 of hub base member 11 preferably comprises an opposed pair of stop members 24, 24, each preferably in the form of a pivotally mounted lever of the second class. Each of the two stop levers 24, 24 preferably has its butt end 25 thereof provided with a hole in which is seated a screw 26 threadably engaged in an internally-threaded socket in the bottom 14 of the housing socket 13 for pivotal mount of that stop lever. The other end of each cam lever 24 is provided with a cam follower 27 having a curved face 28 on its inner side terminating at its root in a notch 29. Between the notch 29 and the pivoted butt end 25, each lever 24 is provided with an abutment-engaging portion 30, which is preferably in the form of a blade, as shown, so as readily to snap into any of the notches on the shaft 18.

Between the cam followers 27, 27 is pivotally mounted an operating cam member 31 which preferably is in the form of a lever pivotally mounted by a screw 32 to the bottom 14 of housing socket 13 opposite the notch 16 in the socket side wall 15. Cam lever 31 has a fan-shaped portion 33 terminating at its sides in radial projections 34, 34, hereinafter called "nodes" with an arcuate surface 35 extending therebetween and preferably formed along the arc of a circle circumscribed about pivot screw 32. Cam lever 31 also has behind each node 34 a cam follower-receiving notch 36. An operating lever arm 37 is fixed to cam lever 31, extends out through the slot 16, and carries a thumb-engaging projection or button 38, so that the cam lever may be flipped back and forth about its pivoting center 32 with application of pressure to opposite sides of the button.

The abutment-engaging portions 30, 30 of the stop levers 24, 24 are biased inwardly toward each other, and thus toward shaft 18 arranged therebetween, by any suitable resilient biasing means. In the embodiment shown in Figs. 1 to 5 inclusive, such resilient biasing means preferably comprises a cam spring member 39 in the form of a C-shaped piece of steel wire seated within the housing socket 13 beyond the butt ends 25, 25 of the stop levers and with the two ends 40, 40 thereof brought up to and curved or bent inwardly to seat in holes in the outer sides of the stop levers in the vicinity of the cam followers 27, 27 thereof. Consequently, those cam followers 27, 27 are biased inwardly toward each other and the cam lever 31 interposed therebetween.

As shown in Fig. 1, a cover plate member 41, preferably cylindrical in shape, is provided with its lower end rabbeted to form a cylindrical projection 42 to seat within the socket flange 15, so as to close off the top of the socket for securely housing within the latter the stop mechanism previously described. Cover plate 41 has a hole 43 coaxially extending therethrough for align-

ment with the hole 17 in the hub base member 11, reciprocatively to receive the plunger shaft 18. To one side of the hole 43 in cover plate 41 is provided a hole within which is rotatably mounted a screw 44 adapted threadably to be received in an internally-threaded socket 45 in the bottom 14 of housing socket 13, so as removably to secure the cover plate to the hub base member 11 in properly oriented position. Cover plate 41 is counterbored on the top side thereof to provide a shallow recess 46, and within that recess there are provided two radially-spaced, internally-threaded holes 47 and 48 for a purpose to be explained later.

The hub assembly 10 is completed by a circular cap plate 49 having an axial hole 50 extending therethrough for alignment with shaft holes 17 and 43 cooperatively to receive the plunger shaft for reciprocative motion. Circular cap plate 49 is adapted to be seated within the recess 46 in cover plate 41. Cap plate 49 has a radial projection 51 on the inner wall of its axial hole 50 to be slidably received in a longitudinally-extending groove 52 formed in a side of shaft 18, to prevent relative rotation between the shaft and the cap plate. The latter also has a hole to one side of its axial shaft hole 50 in which is rotatably mounted an indexing pin 53 having a lower externally-threaded end 54 extending therebelow. The latter is adapted to selective threaded engagement into either of the two internally-threaded holes 47 and 48 in top plate 41, so that plunger shaft 18 may be rotated between and selectively fixed in two positions as are determined by that cooperative engagement so as properly to orient the abutment notches on the shaft with respect to the stop mechanism housed in the socket 13.

With the parts of the embodiment of the device shown in Figs. 1 to 5 inclusive properly assembled; with the stop mechanism housed in socket 13 beneath cover plate 41 secured to hub base member 11 by screw 44, and with cap plate 49 temporarily secured to the cover plate by engagement of index bolt 43 in hole 47 to predetermine delivery of successive dosages of an amount, for example, of about two cubic centimeters (2 cc.); the operation of the device is as follows, as will be more apparent by reference to Figs. 2 to 5 inclusive. The engagement of index bolt 53 in hole 47 aligns the two cubic centimeters (2 cc.) notches 19-19 and 20-20 respectively with the opposed stop blades 30, 30 of stop levers 24, 24. If the cam 31 is swung to the right to the position indicated in Fig. 2 by pressing the thumb button 38 to the left, the stop lever 24 on the left side will be biased by spring 39 toward the shaft 18 so that the curved surface of the latter between those notches 19, 19 will be engaged by that lever's stop blade 30. It will be noted from Fig. 2 that the left cam projection or node 34 will be located opposite the notch 29 in stop lever 24, and the cam follower 27 thereof will be located opposite the notch 36 in the cam lever 31, with that stop lever held free from contact with the cam by contact of its stop blade 30 with the adjacent curved surface of shaft 18.

Upon depression of the plunger shaft 18 in the usual manner of discharging a dosage for subcutaneous injection, the nearest notch 19 will be brought down opposite stop lever blade 30 so that the latter will slide up along the sloping face 21 eventually to be engaged beneath transverse stop face 22 to determine the length of the injec-

tion stroke. As stop blade 30 snaps into notch 19 in that manner, that left hand stop lever 24 having biased motion in toward the axis of shaft 18, cam notch 36 receives cam follower 27 and stop lever notch 29 receives cam node 34, as shown in Fig. 3. In the meantime, the arcuate cam surface 35, engages the cam follower surface 28 of the other stop lever 24 and slides therealong to hold the stop blade 30 of the latter free from contact with shaft 18.

In order to free stop blade 30 of left hand stop lever 24 out of notch 19, the cam 31 is then to be swung over to the other side by flipping cam operating button or projection 38 to the right. During this swinging action of cam 31, the latter will be moved to and eventually through a central neutral position, such as that shown in Fig. 4. In that position, the cam nodes 34, 38 contact the curved faces 28, 28 of the cam followers 27, 27, effectively to hold the stop levers 24, 24 in spread-apart positions shown in Fig. 4, with their stop blades 30, 30 both free from contact with the sides of plunger shaft 18. Then, as the operating lever is thrown further to the right to the position shown in Fig. 5, to swing cam 31 to the left to the other extreme of its path of travel, the left cam node 34 snaps past the end of cam follower 27 of the left stop lever 24 to bring face 28 of that cam follower into contact with the arcuate cam surface 35 to hold stop blade 30 of that left stop lever out of contact with the side of plunger shaft 18. This action, of course, is accompanied by rotation of the right cam node 34 inward away from the past face 28 of cam follower 27 of the right stop lever 24 to the position shown in Fig. 5, so that the stop blade 30 thereof will be biased to contact with the side of the plunger shaft 18. With downward thrust of the plunger shaft 18 thereafter, to discharge the next dosage, notch 20 is brought to receptive relation with respect to stop blade 30 of the right stop lever 24 in a manner similar to the previously described action of the left stop lever 24 with respect to notch 19. As a result, stop blade 30 of the right stop lever 24 is eventually engaged by the transverse top face 22 of notch 20 to stop further downward motion of shaft 18, with notch 29 in right hand stop lever 24 receiving the right cam node 34, and with the right notch 36 in the cam lever 31 receiving the cam follower 27 on that cam lever, as the latter is biased inward to stop or abutment-engaging position. It will be seen that with flip of the operating or control projection or button 38 back to the left position, as shown in Fig. 2, the sequence of operational steps previously described is repeated.

It is to be understood that, although it is preferred cam lever 31 in its central neutral position shown in Fig. 4 so spreads apart the stop levers 24, 24 as to hold their stop blades 30, 30 free from contact with the curved sides of the plunger shaft 18, not only to assure complete freeing of those stop blades alternately from the notches 19-19 and 20-20, but also to permit free reciprocation of the plunger as may be desired, the mechanism will operate effectively if such freedom from contact is not so maintained. For example, if the outer edges of the transverse flat top faces 22-22 of the notches 19 and 20 are chamfered, an operating cam of lesser lateral spread or dimension than 31 might be employed so that the stop levers 24, 24 will be swung out of the notches to a limited degree just sufficient to permit the edges of the stop blades 30, 30 to

pass beyond such chamfered edges, with the latter further camming those stop levers outwardly during plunger depression. In such mechanism, of course, the alternate camming out of the stop levers 24, 24 is accomplished in a manner similar to that described above, but the central neutral position of cam 31 will not hold the stop blades 30, 30 out of contact with the curved sides of the shaft 18. In fact, they will ride in biased contact with the curved sides of the shaft until they successively are approached alternately by notches 19 and 20, which will permit first one and then the other to move slightly in toward received position. However, cam 31 will limit such inward motion so that the stop blade 30 of either stop lever 24 will not move inwardly beyond the chamfered edge of the transverse top face 22 to effect an actual stoppage of longitudinal shaft motion. Actually, the shaft 18 in such varied stop mechanism structure may be reciprocated back and forth with a slight successive clicking noise when cam 31 is in the central neutral position shown in Fig. 4.

In the event that dosages in quantities different from those dictated by notches 19-19 and 20-20 are desired, it is merely necessary for the operator to unthread the lower end 54 of index bolt 53 out of internally-threaded hole 47 in the cover plate 41 and then to rotate cap plate 49 counterclockwise to bring that index bolt to engaging position with respect to internally-threaded hole 48. This, of course, rotates plunger shaft 18 by virtue of the inter-engagement of projection 51 on cap plate 49 with the longitudinal groove 52 in the side of shaft 18, so as to arrange the other series of notches 23-23 opposite the stop levers 24, 24 to bring about cooperation therebetween in a manner similar to that described above in connection with the two series of notches 19-19 and 20-20.

A somewhat simpler construction than that shown in Figs. 1 to 5 inclusive, is shown in Fig. 6, which may be more desirable for economical mass production. The chief differences will be found in the stop levers and their operating cam. Each stop lever 124 is, as shown, of quite simple design requiring a minimum of machining. The inner corner 127 of the free end of each stop lever 124 constitutes the cam follower adapted to ride against the arcuate end surface 135 of cam portion 133 forming one end of cam lever 131. Each stop lever 124 is preferably provided on its inner edge 130 near its free end with a notch 129, and that edge may be sharpened inward of that notch opposite plunger shaft 18 by chamfering the underside thereof to facilitate snapping into the shaft notches.

The cam lever 131 of the Fig. 6 structure is also simplified in design, as shown. Its fan-shaped portion 133 has arcuate end surface 135 thereof terminating in nodes at 134, 134 at both ends where surfaces of opposed side notches or cut backs 136, 136 join therewith. Notches 136, 136 alternately provide clearance for the stop lever followers 127, 127 so that the stop levers alternately can be moved inward by biasing action of common spring 39 to abutment-engaging positions with snap into shaft notches.

Obviously the action of the Fig. 6 structure is quite similar to that of the Figs. 1 to 5, inclusive, construction, with swing of cam lever 131 back and forth when thumb button 38 is flipped to and fro. The follower 127 of one stop lever 124 on one side will ride up out of side cam notch 136, over node 134 and onto arcuate cam surface

135 as thumb button 38 is swung to the opposite side. This moves the engaging edge 130 of that stop lever away from plunger shaft 18 and holds it in such non-engaging position. At the same time the other node 134 is swung inward away from the other stop lever 124 to permit its follower 127 to move into the other cam side notch 136 with biased inward motion of that stop lever's edge 130 to engagement of the plunger shaft 18, so that the latter lever edge may snap into a stop notch in the side of the shaft as the latter is pushed inward to discharge a dosage. Flip back of thumb button 38, of course, reverses that action, and plunger shaft 18 is thus permitted only step-by-step motion as described above, with first one stop lever 124 being permitted to snap into one of the shaft notches 29 and then the other stop lever being permitted to snap into one of the other shaft notches 19 as the first is backed or cammed away and the plunger is pushed inward.

A further advantage is provided by the Fig. 6 structure in that with cam lever 131 swung to its central neutral position, shown therein, its two nodes 134, 134 snap into the opposed notches 129, 129 more securely to hold the parts in such neutral positions with both stop levers 124, 124 held outward away from engagement in notches in plunger shaft 18, so that the latter can be freely reciprocated either to fill the barrel or discharge all of the contents of the latter in one stroke.

In Fig. 7 is shown a further modified form of the stop mechanism of the present invention more readily adapted to installation in a hypodermic syringe structure of the type disclosed in my above identified patent. In fact, the housing of the present Fig. 7 structure is generally similar to that shown in Fig. 7 of that patent with a substitution, however, of an embodiment of the cam-operated stop means of the present invention for the toggle-operated stop means of the patented structure. Thus, the bottom of the enclosing casing constituting a part of the hub assembly comprises the opposed finger-engaging wings 121 and 122, having therein elongated chamber or recess 130 in which is seated an embodiment of the stop mechanism of the present invention. As shown in Fig. 7, the stop levers may be of a somewhat modified form, each comprising an elongated member 224 having a curved cam follower 227 and an extending back end 55 intermediate of which a screw 226 may pivotally mount the same in the bottom of the recess 130 formed in hub assembly base 120. Each stop lever 224 carries between its fulcrum point at screw 226 and its cam follower 227 stop blade 230 for cooperating engagement in the plunger shaft notches. In such an embodiment, the operating cam may also be of modified form, such as that shown at 231, having an arcuate camming surface 235 extending between side notches 236, 236, the corners 234, 234 at the laterally spaced junctions of that surface with those notches constituting the nodes. Cam lever 231 is pivotally mounted by a screw 232 in the bottom of recess 130. The back end of pivotally mounted cam lever 231 is provided with an arcuate rack 58 meshed with a spur idler 57 rotatably supported at 58 by a pin on hub assembly base 120. Spur idler 57 is in turn meshed with arcuate rack 59 on one end of operating lever 190 pivotally mounted at 60 to hub assembly base 120. An operating arm 153 extends from the opposite end of lever 190 through a slot in the end of finger

wing 122 and terminates in a thumb button 125 for back and forth swinging motion.

The stop levers 224, 224 have their cam followers 227, 227 biased toward each other by a common helical spring 239 located between the back lever extensions 55, 55. Thus, during cam operation of each stop lever 224, it acts as a lever of the second class with its working stop blade 230 mounted between the fulcrum point at 226 and the power applying point at cam follower 227. But, as cam surface 235 is freed from contact with cam follower 227 of one of the stop levers 224 with swing of the cam 231 to a position such as that shown in Fig. 7, so that that follower may pass beyond the near corner node to drop into cam notch 236, the biasing force of spring 239 causes that stop lever to move to abutment-engaging position to snap its blade into a notch in the side of the plunger shaft. During such biased motion, the stop lever 224, freed from contact with its operating cam 231, acts as a lever of the first class, with its fulcrum point at screw 226 located between the power application on extension 55 and its work point at blade 230.

The positions of the parts of the embodiments of the stop mechanism shown in Fig. 7 are similar to the positions of the parts of the embodiments shown in Figs. 1 to 5 inclusive, as illustrated in Fig. 5, but at a time somewhat later following indexing of blade 230 of the upper stop lever 224 into notch 20 of plunger shaft 18. In order to free stop blade 230 of upper lever 224 from one of the notches 20 of plunger shaft 18, the thumb button 125 will be swung over to the other side so that lever rack 59 will rotate spur idler 57 in a counterclockwise direction to swing cam rack 56 in a clockwise direction. As a result, cam 231 will swing up to engage upper lever cam follower 227, push it out of upper cam notch 236 over the adjacent corner node, and cause cam surface 235 to ride thereagainst, while holding stop blade 230 of that stop lever out of the path of notch 20 on shaft 18. At the same time, the other lower stop lever cam follower 227 is freed from cam surface 235 past the other corner node, with the other lower cam notch 236 permitting it to move upwardly, so that stop blade 230 of the lower stop lever 224 will be swung up into the path of a shaft notch 19 under the biasing influence of spring 239. Thus, by the swing of the thumb button 125 back and forth, the plunger shaft is permitted successively to move inwardly step-by-step to deliver successive dosages in predetermined amounts similar to the action of the embodiments of Figs. 1 to 5 inclusive, and Fig. 6, as described above.

It will thus be seen that the objects set forth above, among those made apparent from the preceding description, are efficiently attained and, since certain changes may be made in the above construction and different embodiments of the invention could be made without departing from the scope thereof, it is intended that all matter contained in the above description or shown in the accompanying drawing shall be interpreted as illustrative and not in a limiting sense.

It is also to be understood that the following claims are intended to cover all of the generic and specific features of the invention herein described, and all statements of the scope of the invention which, as a matter of language, might be said to fall therebetween.

Having described my invention, what I claim as new and desire to secure by Letters Patent is:

1. Stop mechanism for step-by-step plungers

comprising, in combination, means for guiding along a longitudinal path a reciprocable plunger shaft means having two series of spaced abutment means arranged longitudinally thereof, a pair of opposed pivoted levers located on opposite sides of the path, each lever having an abutment-engaging portion located alongside of the path for successive engagement of the abutment means of one of the two of said series thereof, resilient biasing means biasing said levers toward each other, said levers having opposed cam followers, movable cam means for alternate engagement of said followers with back and forth cam means motions selectively and alternately to move said levers away from said path and to permit them to move theretoward to provide alternate engaging and releasing action of said abutment-engaging portions relative to their respective series of spaced abutment means, and manual operating means to move said cam means back and forth.

2. The stop mechanism as defined in claim 1 characterized by the provision of said resilient biasing means in the form of spring means tending to move said abutment-engaging portions inward toward the path with such biased motion being alternately opposed by cam manipulation.

3. The stop mechanism as defined in claim 2 characterized by the provision of said levers each as a member having a cam follower in the vicinity of one end thereof and a fulcrum mount longitudinally spaced from said follower with said abutment-engaging portion located therebetween.

4. The stop mechanism as defined in claim 1 characterized by the provision of said spring means as a single element engaging both of said stop levers and applying the biasing action to both to tend to move them toward each other.

5. The stop mechanism as defined in claim 4 characterized by the provision of said cam as a pivoted lever having a cam portion located between opposed ends of said stop levers of such dimensions and shape as to hold both of said stop levers simultaneously in non-engaging positions when said cam is in a neutral mid-position and to maintain one stop lever in such position when said cam is swung to one side with simultaneous release of the other stop lever, reversal of that action being had when said cam is swung to the other side.

6. The stop mechanism as defined in claim 5 characterized by the provision of said operating means as a manual lever connected to said cam lever.

7. Stop mechanism for step-by-step plungers comprising, in combination, means for guiding along a longitudinal path a reciprocable plunger shaft means having two series of spaced abutment means arranged longitudinally thereof, a pair of opposed levers of the second class hav-

ing opposed cam followers at opposed ends thereof, means pivotally mounting said levers along opposite sides of the path at fulcrum points longitudinally spaced from said followers, each lever having an abutment-engaging portion located between its follower and its fulcrum point for successive engagement of the abutment means of one of the two of said series thereof, resilient biasing means biasing said levers toward each other, and a pivoted cam lever having a fan-shaped portion located between said opposed followers and adapted to be swung back and forth, said fan-shaped cam portion terminating at the sides in laterally spaced nodes to spread said followers apart and having an arcuate surface extending between said nodes against which said followers are adapted alternately to ride with back and forth cam lever swing, said cam lever having notches behind said nodes with each adapted to receive one follower as the other rides against said arcuate surface so that the engaging portion associated with the received follower is permitted to be biased against the side of said plunger shaft means and the engaging portion associated with the riding follower is held away from contact with said shaft means, said nodes being adapted to ride between said followers to spread them apart to non-engaging positions of said shaft means.

8. The stop mechanism as defined in claim 7 characterized by the provision of opposed notches in said stop levers in the vicinity of their followers simultaneously to receive said nodes as said cam lever is swung to a mid neutral position to hold the parts in positions of non-engagement of said shaft means.

9. The stop mechanism as defined in claim 8 characterized by a common spring resiliently biasing said stop lever followers toward each other.

10. The stop mechanism as defined in claim 9 characterized by a thumb engaging projection mounted on said cam lever and projecting out radially therefrom to an engaging position to permit said cam lever to be swung back and forth thereby.

HAROLD S. AUSTIN.
